(57) **CLAIM**

The ornamental design for a multifunctional wireless charging dock assembly, as shown and described.

DESCRIPTION

FIG. 1 is a front, right and bottom perspective view of a multifunctional wireless charging dock assembly showing my new design;

FIG. 2 is a top, front and left perspective view thereof;

FIG. 3 is top, right and rear perspective view thereof;

FIG. 4 is a front, right and bottom perspective view in a separated state;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines in the figures illustrate portions of the multifunctional wireless charging dock assembly that form no part of the claimed design.
